CUP-MAKING MACHINE

Frederick Ruza, Chicago, Ill., assignor, by mesne assignments, to Paper Container Manufacturing Co., Chicago, Ill., a corporation of Illinois

Application March 22, 1944, Serial No. 527,609

3 Claims. (Cl. 93—36.2)

1

The present invention relates to improvements in cup-making machines. More particularly, it pertains to the manufacture of paper cups in which an adhesively treated web of paper is cut, rolled, and then pressed and finished by means of a novel die carriage device having pressing and finishing dies and related mechanism for operating the same, such as the type disclosed in the Merta Patent No. 2,321,407, and over which the present device is an improvement.

In that type of machine, the pressing and finishing dies carried in the die carriage lacked the necessary relative resiliency positively to accommodate the different layers of paper comprising the cup, such as the many thicknesses in the convolutely wound apex as compared with the single overlap in the cup body. Consequently, improperly formed and leaky cup bottoms often resulted. In addition to this, the lack of relative resiliency between the parts permitted the accumulation of glue and other foreign matter which further tended to aggravate the condition. A large part of the leakage was obtained in rounding the bottom on the cup due to the impact of the forming element at this point. While the rounded cup bottoms seemed to be perfect, it was found that many leaked during use. To overcome this disadvantage, forming rollers having a flanged extension thereon were utilized in connection with the mandrels for aiding in rounding the bottoms of the cups as they were formed and these elements played an important part in the structure of such machines.

Generally, therefore, it is an object of the present invention to overcome the foregoing disadvantages by the provision of a die carriage having relatively resilient dies and with related parts reduced in number, such as those herein described which are positive and efficient in operation and which will function relatively free from mechanical as well as other difficulties and disadvantages.

Primarily, it is an object of the invention to provide a die carriage having a body pressing die to press together an adhesively treated overlap of a cup, and means, resiliently mounted in the carriage and yieldable with respect to the die, to press together adhesively treated layers at the apex of the cup independent of the time of operation of the body pressing die.

More specifically, it is an object of the present invention to provide a reciprocating die carriage for a conical cup-making machine that has means for winding a blank into cup form on a conical mandrel having a frusto-conical

2

body pressing die with a cylindrical extension to press together the adhesively treated overlap of a cup, an apex forming die resiliently mounted within the cylindrical extension to press together convolutely wound adhesively treated layers at the apex of the cup in advance of the body pressing die, and a cup bottom blunting member carried by the apex forming die operated by a hammer member carried by an extension connected to the cylindrical portion, whereby the blunting of the bottom of the cup is obtained after the overlap and convolutely wound layers have been pressed together.

Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention, reference should be had to the following detailed description, taken in connection with the accompanying drawing, in which:

Fig. 1 is a plan view, partly in section and with parts broken away, of a die carriage illustrating a preferred embodiment of the invention;

Fig. 2 is a side elevational view in section, on a somewhat smaller scale;

Fig. 3 is an end elevational view of the die carriage; and

Fig. 4 is a side elevational view of the die carriage on a reduced scale, with parts broken away, and illustrating the driving means therefor.

Referring more particularly to the drawings, there is indicated generally at 10 a reciprocating die carriage slidably mounted on suitable shafts.

This carriage comprises a housing 11 carrying therein a frusto-conical body pressing die 12 and a mechanism, indicated generally at 13, for pressing the convolutely wound layers at the apex of a cup as well as for blunting the bottom thereof.

This mechanism consists of a resiliently mounted apex forming die 14, mounted within a cylindrical extension 15 of the frusto-conical body pressing die 12. The apex forming die 14 has an annular shoulder or flange 16 so that this die is limited in its movement in one direction by the end 17 of the cylindrical extension 15 and by a yoke 18 (each of which carries parts about to be described) in the other direction.

Carried within the central opening of the apex forming die 14 is a cup apex tip blunting pin 19.

This pin is suitably rounded as at 20 to give the proper formation to the cup bottom during the blunting operation, as will more fully appear hereinafter. It should be understood at this point that, if desired, the apex of a cup need not be blunted during the formation of the bottom and, in that event, the blunting pin may be properly counterbored to accommodate the point of a cup without permitting any distortion thereof. The blunting pin has an enlarged portion 21 and an annular flange 22. Around the enlarged portion, which is seated against the shoulder 16 of the apex forming die 14, is a spring 23 which normally urges the pin 19 outwardly so that it is resiliently and slidably mounted in the opening in the head of the apex forming die in which it is carried.

Carried in the yoke 18, in a suitable bearing 24, is a loosely and slidably mounted compensating pin 25. This pin also has an annular flange extension 26 which is adapted to be seated against the portion 22 of the blunting pin 21. This pin 25 functions as a hammer as will more fully appear hereinafter. Actually, the pin 25 during operation is permitted to float, that is, to move freely along its axis toward and away from the flange 22 of the pin 21. This distance of movement of the pin 21 is approximately regulated at about one-quarter of an inch or more.

Attached to the carriage 11 is another bracket or yoke 27 which straddles the pin 25. In this yoke 27 is an adjusting screw 28, the end of which controls the distance through which the pin 25 is permitted free play.

The cup winding mandrel is indicated at 29, the cup rim forming portion at 30, the cup bead forming portion at 31, and the mechanism for driving the bead forming elements are indicated generally at 32. These need no further description since they are generally similar in structure and in operation to those disclosed in the above-mentioned Merta patent.

The entire carriage, including the rim forming mechanism 30, is reciprocated by a very simple crank link 33 attached to a wrist pin 34 suitably secured to the die carriage as indicated generally at 35. The link 33 is eccentrically connected to a crank 36, as indicated at 37.

Operation

In operation the foregoing described elements function as follows: The crank 36 transmits its power through the link 33 and the carriage is constantly reciprocated. The mandrel 29 carrying a cup 38, having an adhesively treated single overlap 39, and an apex consisting of convolutedly wound overlapping portions 40, enters the dies 12 and 14 to be pressed. That is, the action of the crank 36 reciprocates the entire die carriage through the link 33 so that both body pressing die 12 and apex pressing die 13 repeatedly completely cover and uncover the mandrel after a blank has been wound in cup formation thereon. At this point the adhesive is still in a tacky condition and it is desirable by the present operation securely to bond the adhesively treated parts together. It should be noted that normally the apex forming die 14 extends into the body forming die 12 a short distance, as indicated in the dotted line position 41.

In accordance with the principles of the present invention, the apex forming mechanism is first brought into operation to press the convolutedly wound adhesive portions of the cup. The apex forming die 14, because it extends into the

body forming die, is the first to engage the apex of the cup and press the convolutedly wound portions in position. Since it proceeds in advance of the body forming mechanism, this operation is the first to be completed.

Substantially simultaneously thereafter the body forming mechanism begins the pressing of the single overlap and advances to a point at the completion thereof where the apex forming die 10 and the body forming die are in internal surface alignment, as shown in the solid line positions of Fig. 1, as well as in Fig. 2.

Substantially immediately at this point the blunting pin 21 is struck by the hammer pin 25 and urged against the pressure of the spring 23. As the latter is forced into this position by being contacted by the end of the set screw 28, the rounded portion 20 of the blunting pin 19 blunts or rounds off the bottom of the cup to complete the entire bottom forming operation of setting the cup in this area. This delayed action can best be seen as illustrated by the dotted line position 42 of the last described elements and these positions also indicate the approximate distance through which the compensating pin 25 is permitted to float along its longitudinal axis. The various parts of the die carriage are thereafter again restored to their normal position by means of various springs, such as those illustrated at 23, 43 and 44, as the entire carriage is reciprocated in the opposite direction by means of the crank link 33 and crank 36 and into position where the various operations can again be repeated. The springs 43 and 44 are mounted 30 on bolt-like members which function as guide or slide bars while holding the springs which absorb the thrust of the body pressing die 12 immediately after the blunting operation is performed on the cup tip.

It will thus be seen that the objects hereinbefore set forth may readily and efficiently be obtained, and since certain changes may be made in the above construction and different embodiments of the invention could be made without departing from the scope thereof, it is intended that all matter contained in the above description, or shown in the accompanying drawings, should be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. In a conical cup-making machine provided with means for winding a blank into cup form on a conical mandrel, the improvement comprising the combination of a die carriage having a body pressing die to press together an adhesively treated overlap of said cup, and means, resiliently mounted in said carriage and yieldable with respect to said die, to press together convolutedly wound adhesively treated layers at the apex of said cup, said means including a bottom setting mechanism to set the bottom of said cup after said overlap and convolutedly wound layers have been pressed together.
2. In a conical cup-making machine provided with means for winding a blank into cup form on a conical mandrel, the improvement comprising the combination of a die carriage having a body pressing die to press together an adhesively

treated overlap of said cup, and means, resiliently mounted in said carriage and yieldable with respect to said die, to press together convolutely wound adhesively treated layers at the apex of said cup in advance of said body pressing die, said means including a bottom setting mechanism to set the bottom of the cup after said overlap and convolutely wound layers have been pressed together, said mechanism including a cup bottom blunting element and a hammer element to operate said blunting element.

3. In a conical cup-making machine provided with means for winding a blank into cup form on a conical mandrel, the improvement comprising a reciprocating die carriage having a frusto-conical body pressing die to press together an adhesively treated overlap of said cup, said die having a cylindrical extension thereon, an apex forming die resiliently mounted within said extension to press together convolutely wound adhesively treated layers at the apex of said cup

in advance of said body pressing die, a cup bottom blunting member carried by said apex forming die, and a hammer member, carried by a connection on said extension, to cause said blunting member to blunt the bottom of said cup after said overlap and convolutely wound layers are pressed together.

FREDERICK RUZA.
